[57] CLAIM

The ornamental design for a protective cover for an animal carcass, as shown and described.

DESCRIPTION

FIG. 1 is a side, elevational view of a protective cover for an animal carcass showing my new design.

The side opposite that shown in FIG. 1 is substantially the same.

FIG. 2 is a front, elevational view; and

FIG. 3 is a top plan view

Fig. 1

Fig. 3
